WORK CARRIER FOR ELECTROPLATING

Leon J. Pianowski and Sam F. Sgriccia, Detroit,
Mich., assignors to The Udylite Corporation,
Detroit, Mich., a corporation of Delaware

Application April 4, 1947, Serial No. 739,426

12 Claims. (Cl. 105—150)

1

The present invention pertains to a novel work carrier for electroplating of the type that is moved along a cathode rail.

Such a carrier ordinarily has an arcuate surface in engagement with the rail for electrical contact. The quantity of current that can be delivered from the rail to the work is limited by the permissible current density at the area of contact, and this in turn is limited by the area of the arcuate or cylindrical surface. If the surface were elongated, the carrier would bind on the rail while moving over a bend or turn in the rail.

The object of this invention is to provide a carrier that furnishes a greater area of contact with the rail and at the same time does not bind on a curved portion of the rail. This object is accomplished by forming the carrier in two similar members suspended from the rail in substantially the conventional manner and having the usual cylindrical contact surface. These members are in juxtaposition to each other and make contact with one another on protuberances or convex surfaces to permit a rocking action between them while rounding a turn. The cylindrical contacting surfaces are thus shifted out of alignment with each other, and each surface rides on the rail in the usual manner without binding.

The lower ends of the members are formed respectively with hooks overlapping each other in a plane parallel to the axis of the cylindrical contacting surface. The hooks, where contacting each other, are also formed with protuberances or convex surfaces to permit relative rocking in this area. Further, the hooks are joined together by resilient means that maintains the meeting surfaces in contact with each other and yet permit play during the rocking movement.

The invention is fully disclosed by way of example in the following description and in the accompanying drawings in which:

Figure 1 is a plan view of a number of work supports suspended from a rail;

Figure 2 is an elevation on the line 2—2 of Figure 1;

Figure 3 is a section on the line 3—3 of Figure 2;

Figure 4 is an elevation on the line 4—4 of Figure 1;

Figure 5 is a section on the line 5—5 of Figure 4, and

Figure 6 is a section on the line 6—6 of Figure 4.

Reference to these views will now be made by

2

use of like characters which are employed to designate corresponding parts throughout.

In Figure 1 is shown a rail A, such as a cathode rail, from which work supports are to be suspended and along which the supports are to be moved by suitable means such as pushers B.

Each support comprises a pair of hook members 1 and 2 placed one beside the other and substantially identical in formation. Each such member is formed at its end with an extended head 3 having a lower surface 4 formed concavely on the cross sectional radius of the rail A and resting upon the rail, as shown in Figure 5. The cylindrical surface 4 is intended to make electrical contacts with the rail, carrying current from the rail through the hook to work suspended therefrom as will be presently shown.

The shank of each member 1, 2 is offset or bent at 5 in the direction toward the free end of the corresponding head. The lower ends of the members 1, 2 are formed respectively with hooks 6, 7 lying in planes axial of the cylindrical surfaces 4 and overlapping each other as shown in Figures 2 to 6.

25 The width of each head 3, lengthwise of the cylindrical surface 4, is such that the head will slide freely along a bend A' in the rail A and yet make good electrical contact with the rail. Such an arrangement is already known in the art.

30 The quantity of current available to the work is limited by the current density permissible at the surface 4, and this in turn is determined by the area of the surface 4. If the width of the head 3 were enlarged to increase the area of the surface 4, the latter would bind while rounding the bend A'. If two supports were placed side by side, with flat engaging surfaces, the effect would be the same. In the invention, the contacting faces of the mutually adjacent heads are somewhat convex as indicated by the numeral 8 in Figure 1. When on a straight length of rail, these faces engage each other at their outward ends at 9 and recede from each other in the direction inwardly from their point of contact. Thus, when

35 the members 1, 2 are on the bend A' a relative rocking movement thereof on the surfaces 8 takes place, breaking the alignment of the adjacent cylindrical surfaces 4 and permitting the turn to be made without binding on the rail. Preferably the surfaces 8 are in the nature of arcs on a radius smaller than that of the turn A'.

40 The work or the hanger for the work is represented by the member 10 suspended from the overlapped hooks 6, 7. The members 1, 2 are attached to each other by means of lugs 11 extend-

ing downward from the lowermost points of the hooks 6, 7, joined by a bolt 12 carrying a coil spring 13 disposed between one of the lugs and the nut 14 on the bolt. This resilient connection permits the rocking movement of the members 1, 2 relatively to each other as above described.

It is evident that the hooks 6, 7 will also rock relatively to each other, and this motion is facilitated by forming the contacting surfaces of the hooks as convex cylindrical surfaces 15 on a radius equal to that of the cylindrical surfaces 8. The relative position of the hooks when the support is on the bent A' is shown in Figure 6. The two members 1, 2 are maintained in contact with each other at the surfaces 8 by means of the pusher and at the surfaces 15 by the spring 14. Also, both hooks are in contact with the suspended member 10. Although these contact points may be momentarily broken, each member is normally in contact with the rail at its cylindrical surface 4. Nevertheless, complete current interruption at the surface or elsewhere does occur occasionally, and the probability is here reduced 50% by the provision of two members 1, 2. An excessively high current density at a surface 4 tends to destroy the oil film on the rail and to cause welding, scoring and rapid wear of the parts. Further, the heat generated in such an effect is a loss of electrical energy. It is evident that these difficulties are overcome or at least reduced in the present invention by increasing the total area through which current may flow, at the surfaces 4, from the rail to the work.

Although a specific embodiment of the invention has been illustrated and described, it will be understood that various alterations in the details of construction may be made without departing from the scope of the invention as indicated by the appended claims.

What we claim is:

1. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end having a protuberance toward the other member, the two protuberances engaging each other to permit a rocking movement of said members, the lower ends of said members being shaped for the suspension of work therefrom.

2. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end having a protuberance toward the other member, the two protuberances engaging each other to permit a rocking movement of said members, the lower ends of said members being formed with hooks overlapping each other in a plane transverse to the general plane of said surfaces.

3. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end having a protuberance toward the other member, the two protuberances engaging

each other to permit a rocking movement of said members, the lower ends of said members being formed with hooks overlapping each other in a plane transverse to the general plane of said surfaces, the contacting surfaces of said hooks being also formed respectively with mutually contacting protuberances.

4. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end having a protuberance toward the other member, the two protuberances engaging each other to permit a rocking movement of said members, the lower ends of said members being formed with hooks overlapping each other in a plane transverse to the general plane of said surfaces, and resilient means joining said hooks.

5. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end having a protuberance toward the other member, the two protuberances engaging each other to permit a rocking movement of said members, the lower ends of said members being formed with hooks overlapping each other in a plane transverse to the general plane of said surfaces, the contacting surfaces of said hooks being also formed respectively with mutually contacting protuberances, and resilient means joining said hooks.

6. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex to permit a rocking movement of said members, the lower ends of said members being shaped for the suspension of work therefrom.

7. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex to permit a rocking movement of said members, the lower ends of said members being formed with hooks overlapping each other in a plane transverse to the general plane of said surfaces.

8. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex to permit a rocking movement of said members, the lower ends of said members being formed with hooks overlapping each other in a plane transverse to the general plane of said surfaces, the contacting surfaces of said hooks being also convex.

9. A work carrier for electroplating comprising

ing a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex to permit a rocking movement of said members, the lower ends of said members being formed with hooks overlapping each other in a plane transverse to the general plane of said surfaces, the contacting surfaces of said hooks being also convex on a radius equal to that of the first named convex surfaces.

10. A work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex to permit a rocking movement of said members, the lower ends of said members being formed with hooks overlapping each other in a plane transverse to the general plane of said surfaces, the contacting surfaces of said hooks being also convex on a radius equal to that of the first named convex surfaces, and resilient means joining said hooks.

11. In combination, a curved rail, a work carrier for electroplating comprising a pair of similar members adapted at one end for suspension from a rail in juxtaposition and contiguous to each other and adapted for engagement with the rail to an appreciable extent both laterally and longitudinally of the rail, each of the contact-

ing surfaces of said members at said end being convex on a radius less than the radius of curvature of said rail to permit a rocking movement of said members, the lower ends of said members being shaped for the suspension of work therefrom.

12. In combination, a curved rail, a work carrier for electroplating comprising a pair of similar members adapted at one end for suspension from a rail in juxtaposition and contiguous to each other and adapted for engagement with the rail to an appreciable extent both laterally and longitudinally of the rail, each of the contacting surfaces of said members at said end being convex on a radius less than the radius of curvature of said rail to permit a rocking movement of said members, the lower ends of said members being formed with hooks overlapping each other in a plane transverse to the general plane of said surfaces, the contacting surfaces of said hooks being also convex on a radius equal to that of the first named convex surfaces.
